LUBRICATING DEVICE

Elmer G. Gartin, Claremont, N. H., assignor to
Sullivan Machinery Company, a corporation of
Massachusetts

Application June 11, 1931, Serial No. 543,632

18 Claims. (Cl. 184—55)

This invention relates to lubricating devices, and more particularly to improvements in lubricating devices especially adapted to use with pressure fluid motors.

5 An object of this invention is to provide an improved lubricating device. Another object is to provide an improved pressure fluid operated lubricating device. A further object is to provide an improved lubricating device for pressure fluid motors. Yet another object is to provide an improved lubricating device for a pressure fluid motor of the reciprocating piston type wherein pressure fluctuations occur during running of the motor whereby such pressure fluctuations control 10 the lubricating device to regulate the flow of lubricant to the motor parts. Still another object is to provide an improved lubricating device of the pressure fluid operated type wherein lubricant flow is controlled automatically by unbalanced 15 pressures therein and wherein, in the present instance, such unbalanced pressures are due to the pressure fluctuations in the motive fluid inlet of the pressure fluid motor with which the improved lubricating device is associated. These 20 and other objects and advantages of this invention will, however, hereinafter more fully appear.

In the accompanying drawing there is shown for purposes of illustration one form which the invention may assume in practice.

30 In this drawing,—

Fig. 1 is an elevational view of a hammer type rock drill having embodied therein the illustrative form of the improved lubricating device.

Fig. 2 is a transverse sectional view taken on line 2—2 of Fig. 1.

Fig. 3 is a developed vertical sectional view taken substantially on line 3—3 of Fig. 2.

In this illustrative construction the improved lubricating device generally designated 4 is shown embodied in a hammer type rock drill, although it will be evident that the improved lubricating device may be incorporated in tools of various other types. In the present instance, the rock drill is of a standard construction and generally comprises a hammer motor 5 of the pressure fluid operated type, and this motor includes a cylinder 6 having a cylinder bore 7 in which is reciprocably mounted a hammer piston 8 of a usual design, adapted to actuate percussively a drill steel 9 suitably supported within the forward end of the hammer motor. Pressure fluid is supplied to the motor through a hose connection 10 and an inlet passage 12 under the control of a usual throttle valve 13, as shown in Fig. 3. Pressure fluid flows 45 from the inlet passage 12 through inlet ports 14

and suitable distribution passages (not shown) to the motor cylinder under the control of an automatic fluid distributing valve 15 in a well known manner, the distributing valve 15 also controlling the flow of exhaust fluid from the motor cylinder 5. As shown in Fig. 2, the automatic fluid distributing valve is arranged within a valve chest 16, herein arranged in adjacency and with its axis parallel to the axis of the cylinder bore, and the fluid inlet passage in the motor cylinder extends longitudinally and parallel with the distributing valve axis, as shown in Fig. 3.

Now referring to the improved lubricating device 4, it will be observed that formed in a lateral boss 17, herein formed integral with the motor cylinder at one side of the valve chest, is a lubricant reservoir 18, herein in the form of a bore extending forwardly substantially beyond the inlet passage 12, as shown in Fig. 3, and this oil reservoir is provided at its lower end with a suitable 15 filler plug 19. Also formed in the motor cylinder and arranged parallel with the inlet passage and oil reservoir intermediate the same is a passage 20 which communicates at its lower end through a port 21 with the lower end of the lubricant reservoir, and communicates also at its upper end through an oblique restricted passage 22 with the lubricant reservoir. The fluid inlet passage 12 communicates with the upper end of the passage 20, as shown in Fig. 3, through a restricted 20 passageway 23. In the present design, the passageway 22 is of less cross sectional area and of slightly greater length than the passageway 23.

The mode of operation of the improved lubrication device will be clearly apparent from the 35 description given. When the throttle valve 13 is turned into the position shown in Fig. 3, pressure fluid flows through the hose connection 10, past the throttle valve through passage 12 and ports 14 under the control of the automatic distributing valve 15 to the motor cylinder, thereby to effect reciprocation of the hammer piston 8. During running of the hammer motor, it has been found that pressure fluctuations of substantial intensity occur within the motive fluid inlet 40 passage 12, and by these pressure fluctuations the improved lubricating device is controlled. Pressure fluid flows from the passage 12 through passageway 23 and passageway 22 to the upper end of the lubricant reservoir 18. Due to the 45 restricted size of the passageway 22, it is found that the pressure at the upper end of the lubricant reservoir remains substantially constant and substantially greater than the pressure in the passage 12 during running of the hammer motor 50 55

and that the pressure variations which occur in the passage 12 also occur within the upper end of the passageway 20. As a result, the relatively high substantially constant pressure acting on the lubricant at the upper end of the lubricant reservoir causes, upon each drop in pressure within the motor inlet passage, a small quantity of lubricant to be discharged from the reservoir through passage 20 and passageway 23 to the motive fluid supply passage 12 from which the lubricant is entrained by the pressure fluid flowing through the passage 12 and ports 14 to the motor parts to lubricate the latter.

As a result of this invention, it will be noted that an improved lubricating device is provided which is particularly adapted to use with a hammer type rock drill, the lubricating device being of a small compact design attached directly to the side of the motor cylinder. It will further be noted that by taking advantage of the pressure fluctuations within the motor inlet of the hammer motor, it is possible to operate the improved lubricating device in a simple manner with an extremely simple arrangement of ports and passages, and by eliminating all moving parts. These and other uses and advantages of the improved lubricating device will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a lubricating device, the combination with a pressure fluid motor having a fluid inlet passage within which pressure fluctuations occur during running of the motor, of means providing a lubricant reservoir, means forming a passage communicating at its lower end with the lower end of said reservoir and at its upper end with said fluid inlet passage, and means forming a relatively restricted passage connecting said second mentioned passage with the upper end of the lubricant reservoir.

2. In a lubricating device, the combination with a pressure fluid motor having a fluid inlet passage within which pressure fluctuations occur during running of the motor, of means providing a lubricant reservoir, means forming a passage communicating at its lower end with the lower end of the lubricant reservoir, means forming a restricted passageway connecting the upper end of said second mentioned passage with said fluid inlet passage, and means forming a relatively restricted passageway connecting said second mentioned passage with the upper end of the lubricant reservoir.

3. In a lubricating device, the combination with a pressure fluid motor having a fluid inlet passage within which pressure fluctuations occur during running of the motor, of means providing a lubricant reservoir, means forming a passage communicating at its lower end with the lower end of the lubricant reservoir, means forming a restricted passageway connecting the upper end of said second mentioned passage with said fluid inlet passage, and means forming a relatively restricted passageway connecting said second mentioned passage with the upper end of the lubricant reservoir, said second mentioned pas-

sageway being of less cross sectional area than said first mentioned passageway.

4. In a lubricating device, the combination with a pressure fluid motor having a fluid inlet passage within which pressure fluctuations occur during running of the motor, of means providing a lubricant reservoir arranged adjacent to said fluid supply passage, means forming a passage extending longitudinally between said supply passage and said reservoir and communicating 10 at its lower end with the lower end of said reservoir and at its upper end with the fluid inlet passage, and means forming a passageway connecting said second mentioned passage with the upper end of the lubricant reservoir.

5. In a lubricating device, the combination with a pressure fluid motor having a fluid inlet passage within which pressure fluctuations occur during running of the motor, of means providing a lubricant reservoir arranged in adjacency with 20 said fluid inlet passage, means forming a passage extending longitudinally intermediate said fluid inlet passage and said reservoir and having a communication adjacent its upper end of relatively small flow area with said fluid inlet passage and a communication at its lower end of relatively larger flow area with the lubricant reservoir, and means forming a relatively restricted passage connecting said second mentioned passage with the upper end of the lubricant reservoir, the said passages being so proportioned that the pressure fluctuations within the upper end of the reservoir are of less intensity than those in said second mentioned passage.

6. In a lubricating device, the combination with a pressure fluid motor having a fluid inlet passage within which pressure fluctuations occur during running of the motor, of means providing a lubricant reservoir arranged in adjacency with 40 said fluid inlet passage, means forming a passage extending longitudinally intermediate said fluid inlet passage and said reservoir, means forming a relatively restricted passageway connecting the upper end of said second mentioned passage with said fluid inlet passage, and means forming a relatively restricted passage connecting said second mentioned passage with the upper end of the lubricant reservoir, said fourth mentioned passage being of less cross sectional area than said third mentioned passage.

7. In a lubricating device, the combination with a pressure fluid motor having a fluid inlet passage within which pressure fluctuations occur during running of the motor, of means providing a lubricant reservoir, means forming a passage connecting said fluid inlet passage with the bottom of the reservoir, and means forming a relatively restricted passage connecting said second mentioned passage with the top of the reservoir, said restricted passage constituting the sole 60 source of fluid supply for the top of said reservoir.

8. In a lubricating device, the combination with a pressure fluid motor having a fluid inlet passage within which pressure fluctuations occur 65 during running of the motor, of means providing a lubricant reservoir, means forming a passage, means forming a port connecting said second passage with the bottom of the reservoir, means forming a passageway connecting the upper end of said second passage and the fluid inlet passage, and means forming a relatively restricted passageway connecting the upper end of said second passage with the top of the reservoir.

9. In a rock drill, the combination with a per-

cessive motor comprising a cylinder having pressure fluctuations therein during running of the motor and a passage for supplying pressure fluid to said motor, of a lubricating device comprising 5 an elongated lubricant reservoir formed in and extending longitudinally in parallel relation with and along and adjacent to the side of the motor cylinder and having a lubricant therein, the discharge of which from said reservoir to the fluid 10 supply passage is controlled by aforesaid pressure fluctuations, and passage means for conducting pressure fluid from said supply passage to said reservoir and for distributing said lubricant from said reservoir to said supply passage including a 15 relatively restricted passage providing a continuous communication of the reservoir with the supply passage, and a separate passage communicating with the lubricant reservoir and through which lubricant is discharged therefrom.

20 10. In a lubricating device, the combination with a pressure fluid motor having a fluid inlet passage within which pressure fluctuations occur during running of the motor, of means providing an elongated longitudinally extending lubricant 25 reservoir, means forming a passage parallel to said reservoir, means forming a port connecting said second passage with the bottom of the reservoir below the level of the lubricant therein, means forming a passageway connecting said second 30 passage and the fluid inlet passage, and means forming a relatively restricted passageway connecting said second passage with the top of the reservoir above the level of the lubricant, said restricted passageway constituting the sole 35 source of fluid supply for the top of said reservoir.

11. In a rock drill, the combination with a percussive motor including a cylinder having pressure fluctuations therein during running of the motor, of a lubricating device comprising a lubricant reservoir formed in the side of the motor cylinder and having a lubricant therein, the discharge of which from said reservoir is controlled by aforesaid pressure fluctuations, and means forming a lubricant discharge passage having 40 connection at its lower end with the lower end of the reservoir and near its upper end with the upper end of the reservoir, and means forming a passage connecting the upper end of said first mentioned passage directly with the source of 45 fluctuating pressure for admitting the fluctuating pressure to said first mentioned passage, the connection of said discharge passage with the upper end of the reservoir being so proportioned that the pressure fluctuations within the upper end of the 50 reservoir are of less intensity than those in said first mentioned passage.

12. In a rock drill, the combination with a percussive motor including a cylinder having pressure fluctuations therein during running of the motor, of a lubricating device comprising a lubricant reservoir formed in the side of the motor cylinder and having lubricant therein, the discharge of which lubricant from said reservoir is controlled by aforesaid pressure fluctuations, and 55 means forming a lubricant discharge passage having connection at its lower end with the lower end of the reservoir and near its upper end a smaller connection with the upper end of the reservoir, and means forming a passage connecting the upper end of the first mentioned passage directly with the source of fluctuating pressure for admitting the fluctuating pressure to said first mentioned passage, the connection of said discharge passage with the upper end of the reservoir being so proportioned that the pressure fluctu- 60

tions within the upper end of the reservoir are of less intensity than those in said discharge passage.

13. In a rock drill, the combination with a percussive motor including a cylinder having pressure fluctuations therein during running of the motor and a fluid inlet passage, of a lubricating device comprising a lubricant reservoir formed in the side of the motor cylinder and having a lubricant therein, the discharge of which from said reservoir to said inlet passage is controlled by aforesaid pressure fluctuations, and means providing passages including a passage communicating at its lower end with the lower end of the reservoir and near its upper end with a relatively restricted passageway communicating with the upper end of the reservoir, said restricted passageway constituting the sole source of fluid supply for the upper end of said reservoir, and a passage for supplying pressure fluid from said inlet passage to said passage communicating with the lower end of said reservoir.

14. In a rock drill, the combination with a percussive motor including a cylinder having pressure fluctuations therein during running of the motor and a fluid inlet passage, of a lubricating device comprising a lubricant reservoir in the side of the motor cylinder and having a lubricant therein, the discharge of which from said reservoir to said inlet passage is controlled by aforesaid pressure fluctuations, and means providing passages including a passage parallel to the reservoir and communicating at its lower end with the lower end of the reservoir and near its upper end with a relatively restricted passageway communicating with the upper end of the reservoir, said restricted passageway constituting the sole source of fluid supply for the upper end of said reservoir, and a passage for supplying pressure fluid from said inlet passage to said passage communicating with the lower end of said reservoir.

15. A lubricator adapted for connection to a fluid passage within which pressure fluctuations occur continuously during flow therethrough comprising a casing having a lubricant reservoir therein, a passage in said casing parallel and coextensive with the reservoir and communicating at its lower end with the bottom of the reservoir and also communicating with said fluid passage in which the fluctuations occur, and a relatively restricted passage connecting the upper end of said parallel passage with the upper end of said reservoir and constituting the sole source of fluid supply for the upper end of said reservoir, the pressure fluid flowing from said first mentioned fluid passage through said restricted passage to the upper end of the reservoir and the lubricant discharging from the reservoir upwardly through said parallel passage to said first mentioned passage.

16. A lubricator adapted for connection to a fluid supply within which pressure fluctuations occur continuously during flow therethrough comprising a casing having a lubricant reservoir therein, a passage in said casing parallel and coextensive with the reservoir and communicating at its lower end with the bottom of the reservoir and also communicating with said fluid passage in which the fluctuations occur, and a relatively restricted passage connecting the upper end of said parallel passage with the upper end of said reservoir and constituting the sole source of fluid supply for the upper end of said reservoir, a second parallel passage communicating with said fluid supply and through which the

- first mentioned parallel passage communicates with the latter; and a passage connecting the upper end of said first mentioned parallel passage with said second parallel passage, the pressure fluid flowing from said first mentioned parallel passage through said restricted passage to the upper end of the reservoir and the lubricant discharging from the reservoir upwardly through said first mentioned parallel passage to said second mentioned parallel passage, the lubricant discharging from said first parallel passage through said last recited passage to said second parallel passage.

17. A lubricator adapted for connection to a fluid passage within which pressure fluctuations occur continuously during flow therethrough comprising a casing having a lubricant reservoir therein, a passage in said casing parallel and coextensive with the reservoir and communicating continuously through its lower end with the bottom of the reservoir and also communicating with said fluid passage in which the fluctuations occur, and a relatively restricted passage connecting the upper end of said parallel passage with the upper end of said reservoir and constituting the sole source of fluid supply for the upper end of said reservoir, the pressure fluid flowing from said first mentioned fluid passage through said restricted passage to the upper end of the reservoir and the lubricant discharging from the reservoir upwardly through

from the reservoir upwardly through said parallel passage to said first mentioned passage.

18. A lubricator adapted for connection to a fluid supply within which pressure fluctuations occur continuously during flow therethrough comprising a casing having a lubricant reservoir therein, a passage in said casing parallel and coextensive with the reservoir and communicating continuously through its lower end with the bottom of the reservoir and also communicating with said fluid passage in which the fluctuations occur, and a relatively restricted passage connecting the upper end of said parallel passage with the upper end of said reservoir and constituting the sole source of fluid supply for the upper end of said reservoir, a second parallel passage communicating with said fluid supply and through which the first parallel passage communicates with the latter, and a passage connecting the upper end of said first mentioned parallel passage with said second parallel passage, the pressure fluid flowing from said first mentioned parallel passage through said restricted passage to the upper end of the reservoir and the lubricant discharging from the reservoir upwardly through

ELMER G. GARTIN.
